UNITED STATES PATENT OFFICE.

WILLIAM H. PRIESS, OF BELMONT, MASSACHUSETTS, ASSIGNOR TO WIRELESS SPECIALTY APPARATUS COMPANY, OF BOSTON, MASSACHUSETTS, A CORPORATION OF NEW YORK.

ELECTRICAL CONDENSER.

Application filed December 5, 1921. Serial No. 519,868.

To all whom it may concern:

Be it known that I, WILLIAM H. PRIESS, a citizen of the United States of America, and a resident of Belmont, State of Massachusetts, have invented certain new and useful Electrical Condensers, the principles of which are set forth in the following specification and accompanying drawing, which disclose the form of the invention which I now consider to be the best of the various forms in which the principles of the invention may be embodied.

This invention relates to electrical condensers. This application is a continuation in part of my copending application Serial No. 465,137, filed April 26, 1921.

Condensers embodying the present invention are for use generally, but in particular the specific embodiment herein illustrated is adapted for use to interconnect a low loss high-powered radio frequency reservoir circuit and an antenna circuit tuned to the same period. The condenser transfers the energy from the reservoir to the antenna. The condenser of this invention is characterized by being adapted for high voltages and relatively small capacity. As an example of a practical and commercial embodiment of such condenser, it may have a capacity of .00002 mfd. and be capable of withstanding 50,000 volts effective, (70,000 volts maximum) at two amperes and 600 meters maximum.

A feature of the present invention is that the condenser consists of stacks arranged in series parallel with the casing at the midpoint, connecting the stacks of one set in series with the stacks of the other set.

The type of condenser embodying the present invention is known as a mica condenser inasmuch as it usually comprises a stack composed of alternate sheets of foil and dielectric, the foil consisting preferably of a soft material such as lead or tin, and the dielectric consisting preferably of mica, which is one of the best dielectrics known for this purpose.

The stacks each are made up of sections connected in series with separators between the sections, and are clamped and secured within a suitable casing, the casing preferably in service constituting one of the terminals of the condenser, or an electrical connection between stacks.

It has been found that the hysteresis losses in a mica condenser in general increase very rapidly with increased temperature of the mica which results in operating the condenser with the mica at an undesirable point of its phase angle temperature curve. A stack of a mica condenser comprising the alternate sheets of foil and dielectric and in a wax filler, or which has been treated with some suitable wax such as paraffin and embedded in such paraffin, has very low thermal conductivity and therefore under load the heat generated is not properly conducted from the stack, which results in high temperature rise of the stack. This is further accelerated by the hysteresis losses in mica, producing heat, which still further increases the temperature, the process being cumulative, and limits the load that the condenser might carry to a comparatively low value. The thermal path thru a condenser of this type depends on the area of mica sheets and on the length of the stack; that is, the length in a direction at right angles to the plane of the sheets.

In this invention I increase the heat conduction and radiation by utilizing in a condenser of any given electrical characteristics a plurality of stacks each of optimum length for heat conduction instead of a single stack of a length required for a condenser of a given voltage and of a given capacity.

The stack should have a minimum length for obtaining the maximum heat conduction and radiation therefrom. This length, however, in a series section stack having ends at a difference of potential should be such that the length of the creepage path between the ends of the stack is adequate for the potential difference to which the stack is to be subjected. In other words, in this design the minimum stack length that can safely be used for creepage for the voltages employed is incorporated in the design. The stack has a maximum thermal conductivity to the casing and to the high potential terminal.

An object of the present invention is to provide a compact, efficient condenser capable of withstanding comparatively high voltages.

Another object of the invention is to provide a mounting for the condenser having

a minimum as well as an optimum amount of insulation.

Another object of the invention is to provide an improved form of stack.

5 Another object of the invention is to provide a compact, efficient condenser at relatively low cost.

Another object of the invention is to provide a high potential condenser in which 10 the insulation and heat conduction are handled economically and efficiently.

Another object of the invention is to provide a spark-gap that will ensure proper protection irrespective of careless handling 15 of the condenser.

Another object of the invention is to provide a novel form of spark-gap for preventing excessively high differences of potential between parts of the condenser and the subsequent destruction thereof.

Briefly and by way of example, in the embodiment of the invention herein shown and described, I obtain certain of the above objects by providing a condenser casing 25 having two chambers, in each of which is secured a stack or stacks, the casing constituting a midpoint connection or conductor connecting the stacks in the chambers in series and by providing a plurality of terminals projecting thru and insulated from the casing. In prior constructions the effective voltage seldom exceeded 18,000 effective or 25,000 volts maximum. The condenser of the present invention is designed 30 for 50,000 volts effective (approximately 70,000 volts maximum). The construction above outlined is especially adapted for the voltages of higher order herein specified. If only a single-chambered casing were used 35 and one insulated terminal (as in prior constructions), the insulation of the latter would have to be extremely large and expensive, because insulation cost goes up very rapidly with increased voltage, much more rapidly than the ratio of increase of voltage. Also the insulation (the filler within the casing such as wax or oil) between the stack and a single-chambered casing (which is at a difference of potential from portions 40 of the stack or stacks) would necessarily comprise a greater thickness of filler to take care of the greater difference of potential between the stack and casing, the dielectric strength per unit thickness of insulating 45 material decreasing with increased voltage difference. To utilize the designs of prior constructions for the higher voltages herein specified would therefore result in a very heavy, expensive design or construction. Furthermore, the large volume of filler 50 which would be necessary in such prior constructions to withstand the additional voltages it is desired to handle would greatly reduce the thermal conductivity between the stacks and the casing, and therefore pro-

duce a very unfavorable electrical load rating as above explained. I have solved the problem by providing insulators around terminals which are required to withstand but slightly higher voltages than previously used and stacks between which and the casing the insulation is but slightly thicker than in forms previously designed and from which heat conduction and radiation is a maximum, yet the whole condenser is 70 so designed as to withstand voltages of a comparatively higher order such as those above specified.

In the accompanying drawings, I have illustrated one embodiment of the invention 80 in which—

Figure 1 is an elevation thereof with part of the casing broken away;

Fig. 2 is a plan view thereof, with part of the casing broken away;

Fig. 3 is a sectional elevation on the line 3—3 of Fig. 2, looking in the direction of the arrows;

Fig. 4 is an expanded perspective view of a type of stack used in the invention; and

Fig. 5 is a plan view of the construction of Fig. 4.

Referring to the drawings, I have illustrated a casing 10 containing the condenser elements or stacks SS', which casing is preferably of metal and constitutes a mid-point series connection between the stacks, or, if so desired, a terminal of the condenser. In this embodiment, the casing is divided by a metal conductive partition 11 into two chambers 12 and 13, each adapted to receive a pair of stacks SS', or a two-part stack. The casing has an opening at one end, i. e., the bottom, covered by removable closure 14 common to the two chambers 12 and 13 and secured to the casing against a gasket 15 by means of screws 16. At the opposite top end of the condenser casing are openings 17 thru which the high potential terminals and their insulators of the condenser extend, closing the openings as hereinafter described, one of the openings 17 being provided for each chamber, the bottom closure 14, however, being common to both chambers 12 and 13, whereby the latter may be filled with a suitable insulating material W such as molten paraffin or oil.

The stacks SS' consist preferably of alternate sheets of foil and dielectric, preferably mica, and are made up of sections connected in series with separators 18 between the sections in the manner illustrated in Fig. 3 but preferably as illustrated in Figs. 4 and 5 and described hereinafter. The stacks of each pair are arranged horizontally and end to end within the casing; that is, the sheets composing them are arranged vertically with reference to closure 14. The inner adjacent ends of the stacks or stack parts engage a suitable metal pressure mem-

ber 19 having relative high thermo-conductivity, the stacks being arranged in the same straight line and being compressed against the member 19 by means of a pair of metal pressure plates 20 engaging the outer ends of the stacks and compressed against the same by means of metal screws 21 threaded thru the casing and engaging the members 20, the plates 20 and screws 21 having a high thermal conductivity to the casing 10. Thus the outer ends of the stacks have a high thermal-conductivity to the metal casing which is a good radiating means. The outermost section of each stack is electrically connected 15 to the adjacent pressure plate 20 by means of a copper strip lead 22 (Fig. 3) which is secured to the free terminal of the outermost section and bent back between the stack S or S' and the pressure member 20. The inner ends of the stacks are in like manner electrically connected to pressure member 19 by means of flexible copper strip leads 23, which are bent back and interposed between member 19 and the inner ends of the stacks, 25 whereby the stacks are electrically connected at their outer ends to the casing as a common conductor, and at their inner ends to member 19. Each central pressure member 19 is provided with a threaded opening 24, 30 in which is threaded a heavy metal rod or terminal 25, which projects thru the opening 17 to each chamber 12 and 13.

Inasmuch as each high potential terminal 25 must be thoroly insulated from the casing 10, which is at an intermediate potential, I utilize an insulating device 26 for each. In the present embodiment, this insulating device comprises a disc or plate 27 of insulating material, which is of an area greater than the area of the opening 17 in the casing and extending over the boundaries of said opening. This disc is preferably of some material having high insulating qualities and low loss such as mica, and should be so designed as to withstand the difference in potential between the casing 10 and terminals 25. It is preferred that the plate 27 consists of mica, which is one of the best materials for this purpose,—the plate being 50 clamped at its edge to the casing 10 by means of a metal ring 28 and screws 29 passing thru the ring 28 into the casing 10, a suitable gasket 29 being interposed between the mica sheet and the casing 10 to 55 secure a tight joint. The members 25 extend thru the discs 27. Mounted around each terminal 25 below the plate 27 is an insulating bushing 31 of reduced diameter compared to plate 27. This bushing is provided 60 with corrugations or grooves 33 arranged circumferentially therearound to increase the creepage distance between the terminal 25 and casing 10, and consists preferably of a laminated structure; for instance, a plurality of mica pieces or discs of diameter

reduced compared with the disc 27 and compressed together in the manner hereinafter described.

Mounted upon the opposite side of the large mica plate 27 is an insulating bushing 32 of reduced diameter compared with disc 27 and surrounding and insulating the upper portions of the terminal 25. Like the bushing 31, the bushing 32 is also of laminated insulating material preferably built 75 up of superimposed pieces or discs of mica and of decreasing diameter upwardly as illustrated, forming an upwardly tapering bushing.

The insulating device 26 is preferably constructed or assembled on terminal 25 by assembling thereon the mica discs, plates or washers in their proper order. In the embodiment herein illustrated, a nut 34 is threaded on member 25. The mica washers or pieces constituting the bushing 31 are then positioned or assembled on member 25 upon nut 34, then disc 27 is positioned and then the pieces constituting the bushing 32 are positioned on member 25. A round nut 35 is then threaded upon the upper end of member 25 to hold the mica sheets and pieces in position against dislocation. The assembly is then treated in a bath of hot molten insulating material, which will act more or less as an adhesive, for about fifteen minutes until bubbles cease, either with or without the application of vacuum. Suitable materials for this purpose are paraffin, insulation varnish or sulfur. The assembly 100 while hot and impregnated with molten insulating material is compressed or clamped tightly by nut 35 and allowed to cool, thus clamping the mica sheets together in a solid mass held together by nut 35 (which may be pinned to member 25) and by the fusible insulation which has now solidified. The bushing 32 is then cut, turned or ground to proper shape and polished, providing a smooth tapered surface. The bushings 31 and 32 are thus retained and supported on plate 27 and held under compression entirely by means of member 25 and nuts 34 and 35. The grooves 33 are formed by assembling intermediate mica washers of reduced diameter.

Mounted on each terminal 25 above each nut 35, in close electrical contact therewith and with each member 25, is a concavo-convex metal member 36, having its concave side facing the bushing 32 and having its rounded edge 37 in vertical alinement with and spaced from the clamping ring 28. The inclination of the outer surface of the bushing 32 and the curvature and spacing of the member 36 are so arranged with reference to each other and so proportioned that any difference of potential between the opposite ends of the member 25 produces electrical stresses not thru the insulator 32 but mainly 130

thru the air from member 36 to the casing 10, maintaining the electrical field parallel with the bushing 32 instead of cutting the same. In other words, member 36 with casing 10 provides a static shield preventing losses in the insulator 32 and the destruction thereof. The members 36 also perform additional functions in that they provide large-surfaced terminals for radiating heat generated in the stacks and conducted thru the terminals 25 to members 36. The members 36 also serve as protectors or dust-guards for the insulating devices 26, preventing deterioration thereof; that is, each 15 is located above the insulating disc 27 and the bushing 32. Each corona member 36 is secured in place by means of a nut 38 threaded upon the upper portion of the member 25, and above this are located washers 38 and nuts 39 whereby any suitable lead may be attached to the high potential terminal in the usual manner.

The stacks SS' in each chamber may be adjusted as a unit by means of the two pressure screws 21, (Fig. 3) in opposite directions to properly locate each terminal 25 with reference to each other and with reference to its opening 17, whereby the insulating device 26 may be properly clamped 30 in position.

It will be seen that stacks SS' of each chamber are connected in parallel with one another, the inner or mutually facing ends being connected to the common terminal 25, 35 and their outer ends to the casing, the casing 10 in the present instance forming a mid-point connection between the two sets of stacks in the two chambers. Casing 10 connects the two sets of stacks in series with the 40 terminals 25 projecting thru and insulated from the casing.

Thus the four stacks are connected in series parallel between the two condenser terminals 25. The circuit is from one terminal 45 25 to central pressure member 19 in one chamber of the casing, thence in parallel through the two stacks in that chamber abutting said member 19, thence to casing 10, thence to the outer ends of the two 50 stacks in the other casing-chamber, through said latter stacks in parallel to their central abutting member 19 and thence to the other condenser terminal 25.

In order to protect the condenser against 55 excessively high voltages, beyond a value for which the condenser is designed, I have provided a spark-gap device (Fig. 1) which cooperates with each of the shields 36 to form therewith spark-gaps. This spark-gap device comprises a metal rod or stud 40 threaded into the top of the condenser casing 10, in conductive relation thereto (i. e., connected to the midpoint of the condenser between the two sets of stacks) and between and in 60 65 spaced relation to shields 36 of the two ter-

minals 25 from the sets of stacks. The upper end 41^a of the metal rod 40 is threaded. Meshing with the threaded end 41^a is an adjustable conical metal member 42, which may be adjusted vertically to vary the distances between its inclined surface 43 and the adjacent shields 36, providing with shields 36 spark-gaps for protecting each set of stacks SS', the length of the gaps depending on conditions.

The conical member 42 may be locked by a set screw 41 after its correct location is determined for any given condenser.

The distance between members 42 and 36 to form a spark-gap depends on the radius 80 of curvature of adjacent portions of the two parts, the shorter the radius of curvature of such adjacent portions the greater the distance or spacing between them must be to withstand a given difference of potential. In the present design, the distance between the member 42 and each edge 37 of each bell 36 is such as to provide the required spacing to protect the condenser for the given radii of curvature of such adjacent parts, the greater the radius of curvature of such adjacent portions the less the corona effect between the parts at a difference of potential will be and the less the distance may be to protect each set of stacks from voltages exceeding the designed value.

The object of the spark-gap device of the present invention is to protect the condenser by preventing the user from exceeding the rated potential. Axial adjustment of conical member 42 sets a protection of equal value for each half of the condenser. If member 42 is removed from stud 40, for any reason, the spark-gaps consist of stud 40 and the shields 36. The threads on stud 40 have a very small radius of curvature so that when member 42 is removed, the condenser will spark even at a potential lower than the rated voltage or lower than the voltage each set of stacks is designed to stand even tho the length of each gap is thereby increased. If stud 40 also is removed, there will be formed a single spark-gap between the two shields 36 protecting both sets of stacks against voltages exceeding those for which the condenser is designed. In like manner, when the two shields 36 constitute the spaced members of the spark-gap, the condenser will spark over at a potential lower than the total rated voltage, the radii of curvature of the curved edges 37 being so designed to produce this result for a given spacing between shields 36.

I find, for example, in a commercial embodiment of the invention with stud 40 and member 42 in place, as illustrated, and with member 42 positioned to form a gap of $\frac{7}{16}$ inch with each shield 36 the condenser will flash over at approximately 25,000 volts effective from either shield 36 to the mem- 120 125

ber 42. With member 42 removed, the distance between each shield 36 and stud 40 is increased to about $\frac{7}{8}$ inch, but owing to the small radius of curvature of stud 40 or 5 its threads compared to that of member 42, the condenser will flash over around 24,000 or 25,000 from either shield 36 to the stud 40, still maintaining the protection below the designed value. If stud 40 is removed, the 10 distance between the two shields is about two inches, but in this case the gap must handle the entire voltage impressed across terminals 25 and with a given radius of curvature of the edges 37, the condenser will spark over 15 at about 46,000 volts effective.

When stud 40 is removed, the gap formed by the two shields 36 will not protect the condenser in every case because of the conditions existing in the circuit in which the condenser is used. In most cases, however, when the stud 40 and member 42 have been removed, probably thru carelessness, the gap between the shields will be sufficient to protect the condenser. The spark-gap device 25 above described and herein illustrated is "fool-proof". The adjustability of member 42 is a convenience in securing the correct spacing between member 42 and each shield 36, while, if member 42 is removed, there is 30 still maintained a non-adjustable gap between stud 40 and each shield 36 such as to sufficiently protect the condenser. Inasmuch as the members 40-42 are in electrical connection to the casing 10, (a midpoint series 35 connection between the two sets of stacks,) each gap formed between them and one of the shields 36, controls only approximately one-half of the total impressed voltage. But when the two shields 36 form the gap, this 40 gap protects the condenser against voltages exceeding the total designed voltage, altho the length of gap between the two shields is greater than twice the distance between each gap and conical member, 42. Inasmuch as 45 the potential necessary to break down a gap does not vary as a straight line function of the length of the gap, the longer gap will break down at a potential lower than twice the potential necessary to break down one of 50 the shorter gaps.

The construction of the present invention is such that the stacks are securely clamped within the casing and with the terminals and leads thoroly insulated from the casing and 55 from each other. The arrangement of stacks provides a condenser capable of withstanding a high voltage; for example, of the order of 50,000 volts effective and 70,000 volts maximum. At the same time, the condenser 60 may be of any capacity, even of a very low order.

The arrangement of spaced terminals 25 upon the top of the condenser and the electrical connection between the stacks and the

casing 10 allow the use of three different 65 values of capacity in the condenser by—

(1) Employing the two terminals 25 as the circuit connections, in which case the circuit will be as above described in detail.

(2) Employing one of the terminals 25 70 and the casing 10 as the circuit connections, in which case the two stacks in only one chamber will be in circuit, being in parallel with one another.

(3) Employing both of the terminals 25 75 parallel connected together as one terminal and the casing 10 as the second terminal, in which case all four stacks will be in parallel with one another.

It is preferable that the two groups or 80 sets of stacks or elements be of equal capacity so that when used in series, the potential across each stack will be the same. If the groups were of unequal capacities, the potentials would divide inversely as the 85 capacities and the sections of the group of smaller capacity would receive a disproportionately greater strain than the sections of the group of larger capacity. When the groups are connected in series, twice the 90 potential that can be applied to a single group may be applied to the condenser. The capacity of the condenser will then be half the capacity of one of the groups of elements. When the condenser is used with one 95 terminal 25 and the casing as the connections, the potential of a single group can be applied to the condenser and the capacity will be the capacity of a single group of sections. When both terminals 25 are parallel 100 connected and form one of the terminals of the condenser, the potential of a single group may be impressed across the condenser and the capacity of the condenser will be twice the 105 capacity of one of the groups. If the capacity of each group is taken as unity, then the capacity of the first grouping will be one-half, of the second grouping, one, and of the third grouping, two, respectively.

Inasmuch as the stacks SS' of the present 110 invention are composed of sections connected in series, in service there will be a fall of potential from one end of each stack to the other. In this embodiment of the invention, the stacks of each set are arranged substantially parallel to each other, one set in each chamber, the sets being separated from one another by metal wall 11 (Figs. 1 and 2) which receives any heat conducted thru the filler W from the stacks on opposite 120 sides of it. The metal casing, (to reduce the size of the condenser, increase its heat conducting properties, and lower its cost,) is as close to the stacks at all points, consistent with good insulation, as possible. The outer ends of the stacks SS' are electrically and thermally connected to the casing 125 and hence at the same potential therewith.

At points on the stack at substantially the potential of the casing (as at the ends), the casing may be located close to the stacks with increasing separation between them as 5 the potential difference increases as indicated at 44, Fig. 2. The portions 44 of the casing walls between the parallel sets of stacks therefore converge towards each other, forming angular spaces 45 between them, the walls of which may merge with partition 11.

The condenser herein described may be mounted in any suitable manner, but in the present construction, since the casing is a 15 midpoint series connection between the two groups of stacks and hence at an intermediate potential, I utilize an insulating mounting as illustrated in Figs. 1 and 3. As illustrated, there is provided a tubular 20 mounting 46, suitably supported, on which is secured one or more insulators 47 by means of a two-part metal clamp 48, one part 49 being secured to the insulator 47 and the other part 50 securing the insulator to 25 mounting 46 by means of screws 51. Upon the opposite end of the insulator 47 is secured a metal cap 52. The cover 14 of each condenser is provided with lugs 53 (Fig. 3) arranged on a line centrally thereof and to 30 which is secured by means of screws 54 a metal cross bar 55. The condenser is supported centrally on insulator 47 by means of screws 56 projecting centrally thru bar 55 into cap 52. The condenser is thus supported centrally upon a single insulator, being 35 properly balanced thereon. Inasmuch as the casing is at a midpoint potential, the amount of insulation necessary at 47 in the general case is only about one-half of that 40 which would be necessary if the casing were one of the terminals of the condenser.

In Figs. 4 and 5, I have illustrated a form of stack which I prefer for use in the form of condenser herein illustrated, altho the 45 stack therein illustrated is of general application. The showing in Fig. 4 is an expanded view; that is, the several parts of the stack are shown separated for purposes of convenience to more readily illustrate the 50 construction of the stack and the method of building the same. When assembled in the condenser, the several parts are in contact, being suitably clamped together to form a solid stack (either with or without impregnating material adhering thereto as desired or according to conditions), the clamping means being such as disclosed in Fig. 2, the stacks SS' illustrated therein being considered stacks of the type shown in Figs. 4 55 and 5, if so desired.

My improved stack comprises several insulating separators 57 which may consist of several layers of mica (preferably cheap defective mica, inasmuch as such separators 60 are not subject to dielectric strain) micanite

or other similar material. Folded over opposite faces of each separator is a foil sheet 58 forming conducting sheets on opposite sides of the separator connected by an integral connection 59, the parts of the foil 58 upon opposite sides of the separator being spaced inwardly from three edges thereof forming margins 60. The sheets 58 may be very easily folded around the separators with their ends in line, thus properly 75 centering the foil on each separator. The separators 57 are arranged in superimposed position to form a stack with dielectric sheets 61 between opposing conducting sheets 58 of successive separators, 80 this dielectric being preferably a good quality of mica. The separators 57 are so arranged in the stack as to position the connections 59 alternately at opposite sides. The dielectric sheets 61, which are of substantially the same area as the separators 57, are slightly offset, relatively to the separators, alternately at opposite sides as indicated at 62 (Fig. 5) in order better to insulate from each other successive connections 95 59 at successively alternating sides of the stack. Each dielectric 61 with the foil sheets on opposite sides thereof forms one section of the stack, the several sections being connected in series via the alternate integral connections 59. The construction above described is of distinct advantage in being easy to assemble at low cost, and if of special advantage where a stack of low capacity and relatively high voltage is required as in Figs. 100 1-3, since each section comprises two sheets of foil conductors and a single intermediate dielectric 61, each foil sheet engaging a separator 57 and bent around the edge thereof.

The stacks SS' of the present invention, 105 either as illustrated in Figs. 3 or 4, may be constructed and assembled in part in the manner described in my copending application Serial No. 456,903, filed March 30, 1921. The process therein described covers 110 the manufacture of a stack by preliminary dipping the individual sheets of mica in suitable insulating material, such as molten paraffin, and building what is called the material stack consisting of alternate sheets 115 of foil and dielectric, and then treating the material stack thus formed in molten insulating material such as paraffin and applying high compression and cooling, forming a solid block. After this, as in the form illustrated in Fig. 3, the material stack is split up into sections, which are connected in series and the insulating separators between the sections inserted. Of course, the sections 120 may be assembled and connected by any desired method, such as that illustrated in Fig. 4. Or, for instance, each section may be built up under molten wax, heated, compressed and cooled under pressure. Each section is then tested for capacity and volt- 125 130

age. The sections are then connected in series and separators inserted between them. After the sections have been connected by solder and the sectional separators positioned, the two leads are soldered to the free terminals of the end sections. The stack, either form illustrated herein, is then placed on the base of a building stand provided with four vertical rods having vertical notches upon their inner sides adapted to receive the corners of the condenser stack; or, if so desired, a stand having six rods may be used, two rods engaging each side of the stack and one at each end. A stand adaptable for this purpose is disclosed in a pending application of G. W. Pickard, Serial No. 380,919, filed May 12, 1920. The stack when positioned in the stand is supported and braced by the vertical rods against dislocation and side slip. The stack and stand are then placed in a hot molten paraffin bath or a bath of other insulating material for approximately twenty minutes until the stack is warm, the bath being at approximately a temperature of 130° C. The stack and stand are then removed from the bath, and the stack while still in the stand and while still hot, is placed under a pressure of the order of magnitude of a ton per square inch over the active surface of the stack, and allowed to cool under pressure before being placed in casing 10, the vertical rods of the stand supporting and bracing the stack against side slip while under the great pressure. The stack while under the pressure of the order of magnitude above-mentioned and after cooling is tested for capacity, and the capacity finally adjusted to its correct value, if this is necessary. Thus it will be seen that the final and correct capacity can be obtained before the stack is finally clamped in the casing 10 and embedded, thereby avoiding the removal of the filler after finally embedding for the purpose of obtaining the desired capacity, if on test the capacity is found to be wrong. By cooling the stack under pressure outside of the casing in the manner above-described, the stack can also be tested for breakdown before being placed in the casing, as well as measured for final length. Furthermore, by thus waxing and cooling the complete condenser stack, including the separators between sections, before being placed in the casing, it can be handled, as a block and side slip cannot occur during the filling operation after the stack SS' is placed within the casing 10 and maintained under pressure by pressure members 20 and screws 21.

In former processes and methods of building stacks and assembling them within the condenser casing, the wax treating, compression and cooling operations on the completed stack, including the separators in

place, as well as the final adjustment of capacity, usually have been done in a permanent clamp forming part of the condenser and in the condenser casing. In that process, however, it was difficult to maintain good stacks where the length of the stack exceeded by over twice the largest dimension of the base or where sectional separators had been inserted. Such length of stack by reason of the greater number of sections and the greater number of sectional separators tended to cause the side slip above referred to upon final compression; that is, where the stack was relatively high or had separators which had not previously been waxed, or both, upon compression, the elements of the stack tended to be displaced relatively to each other. By providing lateral support for the stack during compression, this difficulty is obviated.

After the stacks SS', including the separators, have been waxed and compressed, cooled and tested as above described, they are in condition to be handled, being cold and covered with wax, and are directly secured within the casing 10 by means of the clamping members 20 and adjusting screws 21 in the manner above described (Fig. 3). The terminal gaskets 29^a are then positioned (Fig. 1) and terminals 25 threaded into block 19 (Fig. 3). The insulators 26, around terminals 25 (Fig. 1), including the discs 27, are then clamped to the casing by means of rings 28 and screws 29. The bells 36 and remaining nuts are then assembled and spark-gap device 42 properly located.

After all the parts have been assembled as illustrated in the drawings, with stacks SS' held under sufficient pressure to hold them in place, the whole condenser can be inverted, the bottom 14 being removed, and casing 10 filled with insulating material W, preferably molten paraffin or oil, in the manner described in my application 456,903 above-mentioned to provide a compact, non-porous, holosteric embedment W for the stacks and around the bushings and terminals within the casing 10, which is free from air and voids. As described in such application 456,903, a head or extension is secured to the casing and the casing and extension are preliminarily heated by filling the same with molten paraffin at a temperature around 140° C. While thus filled, the final pressure is applied to stacks SS' by tightening up screws 21. The molten paraffin is then removed and vacuum applied and the casing and extension filled with molten paraffin or other insulating filler, which is allowed to solidify from the bottom upwardly in the manner described in said application 456,903. In some cases, the preliminary heating with paraffin may be omitted and the stacks SS' finally clamped under high pressure as soon

- as positioned. The condenser stacks and terminals 25 are then embedded, and the head and surplus wax or insulating material removed as described in said application 5 456,903. After the embedment, the bottom 14 with its intervening gasket 15, is secured in place by means of the screws 16.
- The insulators 26, for the purpose of insulating the high potential terminals 25 from 10 the casing, provide a long creepage path with short height. Additional creepage is obtained by providing circumferential grooves in either or both of the mica bushings upon either or both sides of the mica discs 27.
- 15 I have shown such grooves 33 in the mica bushing 31. In the present construction, each insulator 26 comprises a single mica disc 27 clamped to the casing 10, and built-up discs of mica of reduced diameter forming bushings upon and supported by the disc 27, the bushings being clamped to the disc 27 at opposite sides thereof by means of the member 25 and co-operating nuts threaded thereon.
- 20 By the present invention, instead of using one stack, I have used four stacks, each stack having a minimum length consistent with the creepage requirement between the opposite ends of the stack due to voltage differences.
- 25 Each stack has maximum thermal conductivity to the casing and to the high potential terminals. Each high potential terminal is provided on the exterior of the condenser with a corona spark-gap shield constituting a heat-radiating member, the casing 10 constituting the other heat-radiating member. It will thus be seen that each stack, of minimum length, engages at opposite ends conductors having a high thermal conductivity and large heat-radiating powers. The construction and method of building the stack is such that side slip is prevented. The pressure applied to the opposite ends of each stack should be of the order of thousands of 40 pounds per square inch, and of an order which is slightly below a value that will cause spreading of the foil. The structure above-described is such that the stacks are maintained at a minimum temperature for 45 a given load, which results in efficient operation and low loss. In this invention, by placing four short stacks, which are electrically in series parallel with one another and each consisting of series sections, thermally 50 parallel between high-conducting terminals, the thermal path is improved in a ratio of approximately sixteen to one over a single stack having the same electrical characteristics. In this arrangement, I have improved the condenser construction so that it 55 will carry four times the energy of the equivalent single stack with the same heating. In the present invention, also, for the same capacity, I have been able to reduce the 60 amount of mica required in a condenser, thus materially reducing the cost. For instance, in a condenser having a single stack of the same length as the total length of the four stacks of the present condenser and having the capacity of the condenser of the present 70 invention, there would be required mica sheets of four times the area over those required for the condenser of this invention. Furthermore, a much more expensive clamping means would be required to obtain the 75 same pressure per unit area, this clamping means moreover would be inferior and inefficient as well as bulky. In the present invention, by the methods of manufacturing the stack as above-described, and by reason of the minimum length of the stack, side slip has been reduced to a minimum, and the clamping feature simplified while maintaining the high pressure.
- 80 It will be seen, therefore, that the present invention provides a very efficient high tension condenser which is very compact, in which the stacks are maintained under the highest practicable compression to maintain the sheets of foil and dielectric in intimate contact to prevent losses in the stack and to increase its thermal conductivity. The casing forms a heat-conducting and radiating device in contact with the outer ends of the stacks. The inner ends of the stacks, in like manner, have high thermal conductivity to the outside thru blocks 19 and terminals 25, where the heat is radiated by the heat-radiating members 36 upon the terminals.
- 85 It is to be understood that the invention is not limited to the embodiments and features specifically shown and described herein, but that such embodiments and features are subject to changes and modifications 90 without any departure from the spirit of the invention.
- 95 I claim:—
- 100 1. An electrical condenser comprising a plurality of stacks of sheets, a common metal casing for said plurality of stacks by which casing said stacks are connected in series; and a corresponding number of condenser terminals extending from the stacks through the casing and insulated therefrom.
- 105 2. In an electrical condenser, a metal casing, terminals projecting thru said casing and insulated therefrom and a plurality of sets of condenser stacks mounted in the casing with the stacks of each set electrically connected in parallel between the casing and one of the terminals, the sets of stacks being electrically connected by said casing.
- 110 3. In an electrical condenser, a metal casing, terminals projecting thru said casing and insulated therefrom, a plurality of sets of condenser stacks mounted in the casing with the stacks of each set electrically connected in parallel between the casing and

one of the terminals, each stack comprising a number of sections connected in series, the sets of stacks being electrically connected in series by said casing.

5. 4. In an electrical condenser, a plurality of stacks, a metal clamping member surrounding said stacks and electrically connecting them in series and terminals electrically connected to said stacks.

10. 5. In an electrical condenser, a plurality of stacks, each comprising a number of sections connected in series, a metal clamping member surrounding said stacks and electrically connecting them in series at adjacent ends thereof and terminals electrically connected to the opposite ends of the stacks.

20. 6. In an electrical condenser, a plurality of sets of stacks, each stack comprising sections connected in series, a metal clamping member surrounding said stacks, and terminals electrically connected to the stacks, the stacks of each set being electrically connected in parallel between said clamping member and one terminal and the sets being electrically connected in series by said clamping member.

30. 7. In an electrical condenser, a metal casing having a plurality of chambers, condenser stacks mounted in the chambers and electrically connected together thru said casing and terminals projecting thru said casing and insulated therefrom and electrically connected to said stacks.

35. 8. In an electrical condenser, a metal casing having a plurality of chambers, terminals projecting thru said casing at one side and insulated therefrom, a removable closure for an opening in the casing at a side thereof remote from the terminals, said closure being common to the two chambers, a plurality of stacks of short length for heat conduction as compared with a single stack electrically equivalent to the plurality of stacks and mounted within the chambers 40 and electrically connected to said casing and terminals and a filler of insulating material within the casing and surrounding the stacks and terminals and placed therein thru said opening.

50. 9. In an electrical condenser, a metal member, a plurality of stacks mounted within said metal member out of alignment with each other, said member constituting a common electrical connection between the stacks 55 and means electrically connected to the stacks and insulated from said member, for completing the circuit of said condenser.

60. 10. In an electrical condenser, a metal casing, spaced terminals mounted on said casing and insulated therefrom and pairs of stacks arranged side by side within the casing and clamped therein, said stacks comprising series sections and having their outer ends electrically connected to the casing 65 as a common conductor, said terminals

being electrically connected to the intermediate portions of the pairs of stacks.

11. In an electrical condenser, a metal casing, a plurality of sets of stacks mounted within the casing, each stack comprising a number of sections connected in series and composed of foil and dielectric and the stacks of each set being arranged end to end and horizontally within the casing, a central metal pressure member arranged between the inner adjacent ends of the stacks of each set, pressure members engaging the outer ends of said stacks, screws threaded in the casing and engaging said outer pressure members for clamping each set of stacks and supporting them from the casing, terminals 70 engaging in said central pressure members and projecting thru the casing, insulating bushings mounted on said casing and surrounding said terminals for insulating the latter from the casing, metal members mounted on said terminals above said bushings for preventing loss in the bushings 80 and for heat radiation, the stacks of each set being electrically connected in parallel between the casing and one terminal and the sets of stacks being electrically connected in series by said casing, and a filler of insulating material surrounding said stacks within the casing.

12. In an electrical condenser, a metal casing having two chambers, a pair of condenser stacks mounted in each chamber, pressure members, with which the inner ends of the stacks of each pair engage, and adjustable devices threaded thru the casing and engaging the outer ends of the stacks for supporting and clamping them in position, said stacks being electrically connected to said pressure members and to the casing, 100 and terminals connected to said members and projecting thru the casing and insulated therefrom.

13. In an electrical condenser, a casing having a plurality of chambers formed with openings, condenser stacks mounted in said chambers, a filler of insulating material in each chamber surrounding said stacks, and a common closure for the openings in said chambers thru which the filler may be 110 placed within the casing.

14. In an electrical condenser, a metal casing having a metal partition therein forming chambers upon opposite sides thereof and condenser elements mounted in each chamber, said casing and partition conducting and radiating heat from said elements.

15. In an electrical condenser, a metal casing having a partition therein dividing the casing into chambers, stacks mounted in the casing in said chambers and connected together electrically thru said casing, and insulated terminals connected to the stacks and projecting thru the casing from said chambers.

16. An electrical condenser comprising a metal casing, a plurality of short stacks of sheets therein; a corresponding plurality of radiators outside said casing; a corresponding plurality of insulating bushings mounted on the casing and supporting said radiators; and heat-conductors between the stacks and the casing and between the stacks and the several external radiators.
17. An electrical condenser comprising a plurality of stacks of sheets each of which stacks is short for heat conduction as compared with a single stack electrically equivalent to the plurality of stacks; said stacks being arranged end to end in pairs and each pair having a heat-absorbing member located between the adjacent ends; a plurality of heat-radiating means located outside said casing; and a corresponding plurality of heat-conducting condenser-connections extending from said respective heat-absorbing members, through but insulated from said casing, and to said heat-radiating means, respectively; the outer ends of said double stacks being in good thermal and electrical conducting relation with said metal casing.
18. An electrical condenser comprising a plurality of double stacks and a metal casing therefor; and a corresponding plurality of condenser-connections extending from the midpoints of said respective double stacks and through but insulated from said casing; the outer ends of said double stacks being electrically connected to said metal casing, and the half-stacks being short in length as compared with a single stack electrically equivalent with the plurality of stacks.
19. An electrical condenser comprising a plurality of stacks of sheets; a metal casing therefor; heat-absorbing members located respectively in and intermediate the ends of each stack, thereby constituting it a double stack by dividing it into two sections short in length as compared with a single stack electrically equivalent to the plurality of stacks; two heat-absorbing metal clamping members engaging the two ends of each double stack; a plurality of radiating members located outside the casing and electrically insulated therefrom; a plurality of heat-conducting condenser-connections extending between said intermediate heat-absorbing members and said external radiators; and insulated from said casing; and clamping screws traversing the casing-walls, engaging said clamping members, and electrically connecting the ends of the double stacks with the metal casing.
20. An electrical condenser comprising a plurality of stacks of sheets, a metal casing formed with a number of chambers corresponding with the number of stacks, the stacks being located in said chambers and having their outer ends electrically and thermally connected to the casing; heat-radiating means located outside said casing and electrically insulated therefrom; and heat-conducting condenser-connections extending from the midpoints of said stack through and insulated from said casing and extending to said external heat-radiating means.
21. An electrical condenser comprising a metal casing partitioned into a plurality of separate chambers, a stack of sheets located in each chamber; and a plurality of condenser terminals mounted on and insulated from said casing and electrically connected with the midpoints of the respective stacks; the ends of each stack being electrically connected to the metal casing whereby the latter is at a potential intermediate that of said circuit terminals; and an insulating support secured to said casing.
22. An electrical condenser comprising a plurality of stacks of sheets each of which stacks is short for heat-conducting as compared with a single stack equivalent to the plurality of stacks; a metal casing enclosing said stacks and formed with a plurality of chambers; said stacks being arranged in pairs end to end, a pair in each casing-chamber, and the pair in one chamber being located substantially parallel to the pair in another chamber; the ends of the pairs being in good electrical and thermal connection with the casing as a heat radiator; a plurality of radiators mounted on and insulated from the casing; and the adjacent ends of the pairs of short stacks being in good thermal and electrical connection with said external radiators.

WILLIAM H. PRIESS.
